D. A. RITCHIE.
ADVERTISING MACHINE.
APPLICATION FILED AUG. 28, 1916.

1,232,606.

Patented July 10, 1917.

UNITED STATES PATENT OFFICE.

DAVID A. RITCHIE, OF CENTRALIA, ILLINOIS, ASSIGNOR TO ECONOMY ADVERTISING COMPANY, OF CENTRALIA, ILLINOIS, A CORPORATION OF ILLINOIS.

ADVERTISING-MACHINE.

1,232,606.

Specification of Letters Patent. Patented July 10, 1917.

Application filed August 28, 1916. Serial No. 117,252.

To all whom it may concern:

Be it known that I, DAVID A. RITCHIE, a citizen of the United States, residing at Centralia, Illinois, have invented a certain 5 new and useful Improvement in Advertising-Machines, of which the following is a full, clear, and exact description, such as will enable others skilled in the art to which it appertains to make and use the 10 same.

This invention relates to machines of the type that are used for projecting pictures or other subject-matter onto a screen or other suitable surface located some distance 15 away from the machine, and particularly, to machines of the type that comprise a rotatable drum equipped with transparent picture slides, a condenser and a source of light arranged inside of the drum and a 20 projecting apparatus arranged on the outside of the drum in horizontal alinement with the condenser and the source of light, so that the rays from the light will pass through the picture slide that is in operative 25 position and also through the projecting apparatus.

The main object of my present invention is to provide a machine of the type referred to that is particularly adapted for general 30 advertising purposes, in that it is easy to adjust and is not liable to get out of order when in use.

Another object is to provide an inexpensive machine of the general type referred 35 to, in which the projecting apparatus, the condenser, the lighting unit and the reflector that co-operates with the lighting unit are mounted in a novel manner that permits said elements to be adjusted easily. 40 Other objects and desirable features of my invention will be hereinafter pointed out.

Figure 1 of the drawings is a vertical longitudinal sectional view of an advertising machine constructed in accordance with my 45 invention.

Fig. 2 is a horizontal sectional view of said machine; and

Fig. 3 is a perspective view, illustrating a portion of the drum of the machine.

Referring to the drawings, which illustrate the preferred form of my invention, A designates the drum of the machine, which is preferably rotatably mounted in a closed casing B of rectangular shape. 55 A projecting apparatus C is mounted on

the front wall of the casing B in alinement with an opening 1 in said wall and a condenser D is arranged inside of the drum in alinement with said projecting apparatus. The source of light, which preferably consists of an electric lamp bulb E, is arranged inside of the drum behind the condenser D, and a reflector F is arranged behind the lighting unit E, as shown in Fig. 1. Transparent slides G containing 60 pictures or any other subject-matter are mounted on the periphery of the drum in alinement with openings 2 therein, and means is provided for rotating the drum intermittently, so as to bring the slides G 65 into operative position between the projecting apparatus C and the condenser D. 70

The drum A is preferably constructed of sheet metal and the two side members 3 thereof are provided with hubs 4 that revolve freely on a stationary, horizontally-disposed shaft 5 which is supported by hollow brackets 6 on the side walls of the casing B, which brackets are equipped with collars 6^a that bear against the ends of the 80 hubs 4 on the drum, and thus hold the drum centered with respect to the casing B. The slides G are preferably removably mounted on the periphery of the drum, so that they can be arranged in different positions or be 85 replaced by different slides, and while it is immaterial what means is employed for holding the slides in position, I prefer to provide the drum with pairs of angle-shaped clips 7 that embrace the longitudinal 90 edge portions of the slides, a pair of clips 7 being provided for each slide, and the slides being prevented from moving longitudinally of their supporting clips by 95 means of spring arms 8 that lap over the ends of the slides. The arms 8 can be formed conveniently from pieces of spring wire that are soldered or connected in any other suitable manner to the clips 7, as shown in Fig. 3. 100

The condenser, the lighting unit and the reflector are adjustably mounted on a structure arranged inside of the drum and carried by the shaft on which the drum revolves, which structure is preferably composed of pieces of pipe or tubing and pipe fittings that are detachably connected together in such a manner that the condenser, lighting unit and reflector can be raised or lowered, can be moved horizontally toward 110

or away from the projecting apparatus and can also be turned about horizontal axes into various angular positions. The main supporting element of the structure referred to consists of a horizontally-disposed member 9 that passes through a sleeve 10 mounted on the upper end of an upright 11 which is stationarily mounted on the shaft 5, the member 9 being adapted to be adjusted horizontally or longitudinally of its length in the sleeve 10. The condenser D is carried by a rod 12 adjustably mounted in a sleeve 13 which is carried by a sleeve 14 that is adjustably mounted on the main supporting element 9 of the structure, the lighting unit E is carried by a rod 15 that passes through a horizontally-disposed sleeve 16 carried by a vertically-disposed sleeve 17 adjustably mounted on a vertical support 18 that depends from a sleeve 19 which is adjustably mounted on the main supporting element 9, and the reflector F is carried by a rod 20 that passes through a vertically-disposed sleeve 21 carried by a sleeve 22 which is adjustably mounted on the supporting member 9. The various sleeves above referred to preferably consist of T-shaped pipe fittings, and set screws or other suitable fastening devices 25 are employed to adjustably connect said sleeves to the rods or parts that pass through same. The condenser D is pivotally connected to the rod 12, so that it can be swung sidewise with relation to said rod, and the reflector F is also pivotally connected to the part 20 that carries same, so that it can be swung upwardly and downwardly, and thus enable it to be adjusted accurately to the lighting unit E with which it cooperates. Any suitable clamping means can be used to hold the condenser and reflector in adjusted position, such, for example, as wing nuts 26 on the bolts that connect the condenser and reflector to the parts that carry same.

The projecting apparatus C comprises portions 27 and 28 that are pivotally connected together at 29, and the portion 27 is adjustably mounted in parallel guides 30 on the front wall of the casing of the machine, thereby enabling the projecting apparatus to be adjusted easily into proper position, by raising or lowering the portion 27 or by swinging the portion 28 on its pivots, said parts being so constructed that they are held in adjusted position by frictional pressure. The shaft 5 on which the drum is mounted is hollow, so that the electrical conductors 31 which supply current to the lighting unit E can be led into the drum through said shaft, as shown in Fig. 2, and a switch 32 is provided for governing the lamp circuit, said switch being arranged inside of the casing B, as shown in Fig. 1, and the portions of the conductors 31 that extend from said switch to the

shaft 5 being incased in a conduit 33. The side members 3 of the drum are provided with openings 34 through which the air in the drum and in the casing can circulate, and air inlet openings and outlet openings 35 and 36, respectively, are formed in the casing, preferably at the lower and upper ends of the front wall of the casing, so as to permit cold air to enter the casing, circulate through the drum and then escape through the upper portion of the casing after it has become heated by the lighting unit E.

Any suitable mechanism may be used for rotating the drum intermittently, the mechanism herein illustrated for this purpose consisting of an electric motor 37 arranged inside of the casing B, as shown in Fig. 1, and connected by means of a belt 38 with a pulley 39 on a shaft 40 equipped with a worm 41 which meshes with a gear 42 on a shaft that is provided with a disk 43, to which a pawl 44 is eccentrically connected. The pawl 44 cooperates with pins 45 that project laterally from one side of the drum A, and a coiled spring 46 is employed for normally holding said pawl in position to cooperate with said pins. When the motor 37 is in operation the pawl 44 moves upwardly and downwardly and cooperates with the pins 45 in a well known manner to impart a step by step movement to the drum A. The pawl 44 is guided by a bracket 47 on the rear wall of the casing B, and a friction brake 48 is arranged in the upper portion of the casing in the manner shown in Fig. 1, so as to exert sufficient frictional pressure on the drum to prevent it from overthrowing, said brake being provided with a turn buckle or other suitable means 49 that can be adjusted so as to vary the frictional pressure that the brake exerts on the drum. Doors 50 are formed at suitable points in the walls of the casing B, so as to enable the slides in the periphery of the drum to be changed and the supporting structure for the condenser, the lighting unit and the reflector to be adjusted. The electrical conductors that lead to the motor 37 are preferably incased in a conduit 33 arranged inside of the casing, and a switch 51 is provided for controlling the motor circuit.

Having thus described my invention, what I claim, and desire to secure by Letters Patent, is:

1. A machine of the character referred to, comprising a rotatable slide holder, a vertically adjustable projecting apparatus arranged on the outside of said holder, a stationary supporting structure arranged inside of said slide holder, and a lighting unit, a reflector and a condenser mounted on said structure in such a manner that they can be adjusted vertically and horizontally.

2. A machine of the character referred to,

comprising a rotatable slide holder, a pivotally mounted projecting apparatus arranged on the outside of said holder, a lighting unit arranged inside of said holder, a condenser and a reflector arranged in front of and in rear of said lighting unit, respectively, and supporting devices to which said condenser and reflector are pivotally connected.

3. A machine of the character referred to, comprising a rotatable slide holder, a projecting apparatus arranged on the outside of said holder in such a manner that it can be adjusted vertically and also swung about a horizontal axis, a lighting unit arranged inside of said holder, a condenser and a reflector arranged in front of and in rear of said lighting unit, respectively, supporting devices to which said condenser and reflector are pivotally connected, and means for enabling said condenser and reflector to be adjusted vertically and horizontally.

4. A machine of the character referred to, comprising a rotatable slide holder, a projecting apparatus arranged on the outside of said holder, means for enabling said apparatus to be raised and lowered and also turned about a horizontal axis, a lighting unit arranged inside of said holder, a condenser, and a reflector arranged in front of and in rear of said lighting unit, means for enabling said condenser, lighting unit and reflector to be adjusted horizontally, and means for enabling said condenser and reflector to be set at an angle with relation to the lighting unit.

5. A machine of the character referred to, comprising a rotatable slide holder, a lighting unit arranged inside of said slide holder, a projecting apparatus arranged outside of said slide holder, means for enabling said projecting apparatus to be adjusted angularly and also raised and lowered, and means for enabling said lighting unit to be adjusted vertically and horizontally.

45 6. A machine of the character referred to, comprising a casing, a rotatable slide holder in said casing, a projecting apparatus comprising two parts pivotally connected together, one of which is mounted on the exterior of said casing in such a manner that it can be adjusted vertically, a lighting unit arranged inside of the slide holder, and means for enabling said lighting unit to be adjusted vertically and horizontally.

55 7. A machine of the character referred to, comprising a casing, a rotatable slide holder arranged inside of said casing, a projecting apparatus mounted on the exterior of the casing, means for enabling said projecting apparatus to be tilted into an angular position and also moved upwardly and downwardly, a stationary supporting structure arranged inside of said slide holder, and a lighting unit, a condenser and a reflector mounted on said supporting structure in

such a manner that they can be adjusted vertically and horizontally.

8. A machine of the character referred to, comprising a casing, a slide holder rotatably mounted inside of said casing, a projecting apparatus comprising two parts pivotally connected together, vertically-disposed guides on the exterior of said casing in which one of said parts is slidably mounted, a shaft that supports said slide holder, a stationary supporting structure carried by said shaft, and a condenser, a lighting unit, and a reflector adjustably mounted on said supporting structure.

9. In a machine of the character referred to, a drum provided on its periphery with means for supporting transparent slides, a projecting apparatus, a horizontally-disposed shaft on which said drum is rotatably mounted, a standard on said shaft, a horizontally-disposed member carried by said standard, a condenser, a lighting unit and a reflector arranged inside of said drum, and depending devices on said horizontally-disposed member that carry said condenser, lighting unit and reflector.

10. In a machine of the character referred to, a drum provided on its periphery with means for supporting transparent slides, a projecting apparatus, a horizontally-disposed shaft on which said drum is rotatably mounted, a standard on said shaft, a horizontally-disposed member carried by said standard, a condenser, a lighting unit and a reflector arranged inside of said drum, depending devices on said horizontally-disposed member that carry said condenser, lighting unit and reflector, said depending devices being adapted to be moved longitudinally of said horizontally-disposed member, and means for enabling the elements carried by said device to be adjusted vertically with relation to said projecting apparatus.

11. In a machine of the character described, a rotatable drum provided with means for supporting transparent slides, a horizontally-disposed shaft on which said drum is rotatably mounted, a lighting unit, a condenser and a reflector arranged inside of said drum, a stationary standard on said shaft, a horizontally-disposed supporting member on said standard, sleeves adjustably mounted on said member, and depending devices carried by said sleeves for supporting said condenser, lighting unit and reflector.

12. In a machine of the character referred to, a drum provided on its periphery with pairs of flanged members that constitute open ended slide holders, and pivotally mounted resilient retaining devices on said flanged members that engage the ends of the slides and thus prevent them from moving longitudinally out of said holders.

13. In a machine of the character referred to

to, a casing, a drum rotatably mounted on the inside of said casing and provided with means for supporting transparent slides, means for imparting a step by step movement to said drum, and an adjustable band arranged inside of said casing, tangential to said drum so that it will exert frictional pressure on the periphery of said drum so as to prevent the drum from overthrowing, and means for varying the tension of said band.

14. A machine of the character described, comprising a casing, a projecting apparatus adjustably mounted on said casing in alignment with an opening formed in one wall

thereof, a drum rotatably mounted inside of said casing and provided on its periphery with means for supporting transparent slides, a stationary hollow shaft that extends transversely through said casing so as to support said drum, a stationary supporting structure mounted on said shaft and composed of a plurality of elements that are adjustably connected together, an electric lamp bulb carried by one of said elements, and supply conductors for said lamp bulb that are led into the drum through said hollow shaft.

DAVID A. RITCHIE.
